Primary Examiner — Charles Hanson(57) **CLAIM**

The ornamental design for a lateral stability wheel, as shown and described.

DESCRIPTION

FIG. 1 is a perspective view of a lateral stability wheel mounted on a three wheel powered cart;

FIG. 2 is an enlarged perspective view of the lateral stability wheel;

FIG. 3 is an enlarged side elevational view of the lateral stability wheel; and,

FIG. 4 is a rear elevational view of the lateral stability wheel. The broken line showing of the three wheel powered cart is included for the purpose of illustrating environment and forms no part of the claimed design.
